WILLIAM F. DOENGES, OF SAN ANTONIO, TEXAS

SAFETY COMBINATION LOCK

Application filed March 29, 1930. Serial No. 439,878.

In combination locks as now made, each tumbler has an opening which, when aligned with the other tumbler openings, permits the cooperating lock element to drop into the same. These openings can readily be made visible from the outside of the doors by means of certain forms of electric rays, thus making it possible for a burglar easily to open the doors.

The object of the present invention is to produce a combination lock having tumbler openings which cannot be rendered visible in the manner just described.

In accordance with my invention, I so construct the tumblers and bolt that the openings or recesses in the tumblers do not extend through the entire thickness of the latter but are closed on at least one side, so that in side elevation the tumblers appear to have uninterrupted peripheries. The openings or recesses in the tumblers are made shallow compared with the notch in the drive wheel, so as still further to reduce the possibility that the tumbler recesses or openings may be rendered visible through the use of electric or other rays passing inwardly through the door. Then, instead of making the tumbler end of the bolt solid, as heretofore, I divide it into relatively movable parts, one of which is adapted to enter the notch in the drive wheel to permit the bolt to assume its release position; the remainder, moving through a shorter distance than that required to produce an unlocking condition, being adapted to enter the recesses in the tumblers. Suitable interlocking means between the parts of the bolt lock the bolt against completing its releasing stroke until all of the tumblers have been brought into a predetermined angular position, whereupon the bolt is freed so that it may complete its travel into the unlocking position when the notch in the drive wheel is brought to the proper point.

The various features of novelty whereby my invention is characterized will herein-after be pointed out with particularity in the claims; but, for a full understanding of my invention and of its objects and advantages, reference may be had to the following de-

tailed description taken in connection with the accompanying drawings, wherein:

Figure 1 is a side elevation of a dial-controlled combination locking device, the tumbler casing being shown in section; Fig. 2 is an end view of the device, looking at the right hand end of Fig. 1; Fig. 3 is a section taken on line 3-3 of Fig. 1, on a somewhat larger scale; Fig. 4 is a section taken on line 4-4 of Fig. 1, on the same scale as Fig. 3, and the visible tumbler being shown partly in section; Fig. 5 is a side or edge view of the tumblers and drive wheel, on the same scale as Figs. 3 and 4, separated from the remainder of the lock device; Fig. 6 is a plan view, on a larger scale, of the tumbler end of the bolt, being a section taken on line 6-6 of Fig. 2, and all of the parts except the bolt being omitted; Fig. 7 is an end view of the bolt, looking at the left hand end in Fig. 6, portions of the drive wheel and tumblers being shown in operative relation thereto; Figs. 8, 9, and 10 are views partly in section and partly in elevation, showing the tumbler end of the bolt and fragments of the drive wheel and tumblers respectively; and Figs. 11 and 12 are respectively a side and an edge view of the locking block between the relatively movable parts of the bolt.

Referring to the drawings, 1 represents a combination lock case, 2 the dial, 3 the operating shaft, and 4 the drive wheel of any usual or suitable combination lock. Within the case are any desired number of tumblers 5, also of any usual or suitable construction, except as hereinafter indicated. The drive wheel has in the periphery a deep notch 6 into which the lock bolt or a part thereof enters in moving to its release position. The bolt may take any suitable form. In the arrangement shown, the bolt consists of a heavy dog-like member 7 pivotally mounted on the combination lock casing by means of a pin or screw 8 passed through the same and into the casing toward one end of the bolt. The short end of the dog is provided with a nose 9 adapted to register with the notch in the drive wheel when the latter occupies a predetermined angular position, and to enter the notch through the action of gravity assisted,

if desired, by means of a spring 10 between the dog and the casing.

In the ordinary lock of this type the nose

on the bolt is wide enough to extend across all of the tumblers as well as across the drive wheel; the tumblers being provided with notches similar to those in the drive wheel,

whereby the notches in the tumblers and in the drive wheel must all be brought in line in

10 order to permit the bolt to move into its release position. In accordance with my invention, I make that part of the bolt that engages with the tumblers separate from that part

15 that co-operates with the drive wheel; uniting the parts together, however, in such a manner

20 that they will have capacity for limited relative movements and be interlocked with each other to a certain extent. By this means the

25 bolt elements that engage the tumblers need have only small movements compared to the

30 movement of the bolt as a whole, and therefore the notches or recesses in the tumblers need not be deep but may be quite shallow.

In the arrangement shown, what may be

25 termed the auxiliary nose elements 11 of the bolt are in the form of teeth on a swinging

block 12 hinged to the bolt by means of a suitable hinge pin 13; the parts being so proportioned that the teeth lie in a row beside

30 the nose 9 but may be swung up and down with the block. A spring 14 fixed at one end

35 to the body of the bolt, and underlying a pin 15 projecting from the side of the block 12, tends constantly to hold the block in such

40 a position that the teeth project somewhat above the nose 9. Therefore, when the nose

45 9 is riding on the uninterrupted part of the periphery of the drive wheel, the auxiliary nose elements may ride in grooves 16 extend

50 ing around the peripheries of the tumblers. Each tumbler has, instead of a deep notch

55 similar to that in the drive wheel, a small recess 17 opening from the bottom of the peripheral groove. In other words, the notch

60 element of each tumbler is open only at the periphery and not at the sides of the tumbler so that, in side elevation, each tumbler has an uninterrupted circular outline. When

65 the recesses in all of the tumblers are brought into line opposite the teeth on the bolt, the

70 swinging block on the bolt is moved by the spring so as to cause the teeth to enter the recesses, even though the nose 9 be still riding

75 on the unmutilated part of the drive wheel. Then, when the drive wheel is

80 brought into such position that its notch is in line with the recesses in the tumblers, the

85 nose 9 enters the notch, due to the fact that the bolt as a whole may now swing bodily

90 even though the block 12 has reached the limit of its swinging movement.

Some means must be provided to prevent

95 the bolt from swinging into its release position whenever the notch in the drive wheel

100 registers with the notch on the bolt unless,

at the same time, the teeth or auxiliary bolt elements are seated in the recesses in the tumblers. This is accomplished by interlocking the block 12 and the bolt in such a manner that the bolt cannot normally swing to-

70

ward the axis of rotation of the drive wheel, but is freed for such swinging movement upon the entry of the teeth or auxiliary bolt elements into the recesses in the tumblers. In the arrangement shown, this is accomplished 75

by means of a locking block 18 extending through and slidably in the block 12; the locking block being pivotally connected at its lower end, as indicated at 19, to the bolt proper.

The locking block has therein a long L-shaped 80 slot 20 whose long arm extends lengthwise of the locking block, and whose short arm, at the upper end of the block, extends crosswise.

In the block 12 is a short diagonal slot 21 of a length about equal to that of the short 85

arm of the slot 20. A pin 22 extends through the slots 20 and 21. Normally the parts are

as shown in Fig. 8, the nose 9 and the teeth 11 riding on the peripheries of the drive wheel and tumblers, respectively. One end 90

of the diagonal slot 20 registers with the short arm of the slot 21 at or near the free end of the latter. It is at this point that

the pin 22 is situated. It will be seen that if it be attempted to swing the bolt in a clock- 95

wise direction, the pin 22 serves as a positive lock as long as the teeth 11 remain out of the recesses in the tumblers. When the tumblers are turned so as to bring the recesses there- 100

in into registration with the teeth 11, as indicated in Fig. 9, the spring 14 forces the block 12 up. This upward movement of the block 12 is permitted because the lower edge of the

inclined slot 12 serves a wedge that will push the pin 22 toward the right. The parts are 105

so proportioned that the movement of the pin 22 brought about by the seating of the teeth on the block 12 in the recesses in the tumblers is such as to bring the pin directly at the upper end of the long arm of the slot 20, as

shown in Fig. 9. The bolt elements and the tumblers remaining in the positions indicated in Fig. 9, it is only necessary to turn the drive wheel until the notch 6 registers with the nose 9, as indicated in Fig. 10. It will

110 be seen that in Fig. 9 the pin 22 no longer serves as a lock to prevent the upward move-

ment of the left hand end of the bolt and, therefore, as soon as the drive wheel reaches

115 the position indicated in Fig. 10, gravity and the spring 10 will swing the bolt in the clock- wise direction; the locking pin 22 simply rid-

120 ing in the long arm of the slot 20 and the block 12 remaining stationary or at least having no

further movement toward the axis of rotation 125

of the tumblers.

When the dial is turned backward to re-

turn the locking dog or bolt to its locking

position, the inclined side 23 of the notch or

depression in the drive wheel, as best shown

in Fig. 10, pushes the dog or bolt down until the nose rides on the periphery of the wheel. Then, when the drive wheel catches the first tumbler and the tumbler begins to turn, the block 12 is pushed down so as to withdraw all of the teeth from the recesses in the tumblers; the parts being then all in the condition shown in Fig. 8.

It will thus be seen that I have produced a simple and novel combination lock device in which the tumbler openings or recesses are of such a character, and are so located, that it will be to all intents and purposes impossible to disclose their locations by means of electric rays that would make all of the usual tumbler openings visible to a person on the outside of the door. It will also be seen that I have accomplished my purpose in a simple way and by means of only a few additional parts.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A combination lock mechanism comprising a driving wheel having a peripheral recess, a locking bolt adapted to enter said recess in assuming a release position, tumblers having peripheral recesses, an element pivotally mounted on the locking bolt and having tumbler-engaging portions adapted to enter the recesses in the tumblers in assuming a release position, and interlocking means between said locking bolt and said element whereby said locking bolt is prevented from entering the peripheral recess in the driving wheel until after the tumbler-engaging portions of the element have entered the peripheral recesses in the tumblers.

2. A combination lock mechanism comprising a driving wheel having a peripheral recess, a locking bolt adapted to enter said recess in assuming a release position, tumblers having peripheral recesses, an element pivotally mounted on the locking bolt and having tumbler-engaging portions adapted to enter the recesses in the tumblers in assuming a release position, and a locking block mounted on the locking bolt and provided with means cooperating with the element having the tumbler-engaging portions to prevent the locking bolt from entering the peripheral recess in the driving wheel until after the tumbler-engaging portions of the element have entered the peripheral recesses in the tumblers.

3. A combination lock mechanism comprising a driving wheel having a peripheral recess, a locking bolt adapted to enter said recess in assuming a release position, tumblers

having peripheral recesses, an element pivotally mounted on the locking bolt and having tumbler-engaging portions adapted to enter the recesses in the tumblers in assuming a release position, and a locking block ⁷⁰ pivotally mounted at its lower end on the locking bolt and provided with means cooperating with the element having the tumbler-engaging portions to prevent the locking bolt from entering the peripheral recess in the ⁷⁵ driving wheel until after the tumbler-engaging portions of the element have entered the peripheral recesses in the tumblers.

4. A combination lock mechanism comprising a driving wheel having a peripheral recess, a locking bolt adapted to enter said recess in assuming a release position, tumblers having peripheral recesses, an element pivotally mounted on the locking bolt having tumbler-engaging portions adapted to enter the recesses in the tumblers in assuming a release position and having a slot extending transversely therethrough, a locking block mounted on the locking bolt and having a slot extending transversely therethrough, and a pin ⁸⁰ mounted on the locking bolt and extending through the slots in the pivotally mounted element and in the locking block whereby said locking bolt is prevented from entering the peripheral recess in the driving wheel until after the tumbler engaging portions of the element have entered the peripheral recesses in the tumblers.

5. A combination lock mechanism comprising a driving wheel having a peripheral recess, a locking bolt adapted to enter said recess in assuming a release position, tumblers having peripheral recesses, an element pivotally mounted on the locking bolt having tumbler-engaging portions adapted to enter the recesses in the tumblers in assuming a release position and having a diagonal slot extending transversely therethrough, a locking block pivotally mounted at its lower end on the locking bolt and having an inverted L-shaped slot extending transversely therethrough, a pin mounted on the locking bolt and extending through the slots in the pivotally mounted element and in the short arm of the inverted L-shaped slot in the locking block to prevent relative movement between said locking bolt and said tumbler-engaging portions, and means to move the tumbler-engaging portions into the tumbler recesses when said tumblers assume a release position, the movement of said tumbler-engaging portions freeing the pin from its position within the short arm of the L-shaped slot in the locking block and permitting the locking bolt to move into the recess in the driving wheel to release said locking bolt.

6. A combination lock mechanism comprising a driving wheel having a peripheral recess, a locking bolt adapted to enter said recess in assuming a release position, tumblers

- having peripheral recesses, an element pivotally mounted at its inner end on the locking bolt having tumbler engaging portions at its outer free end adapted to enter the recesses in the tumblers in assuming a release position and having an intermediate diagonal slot extending transversely therethrough, a locking block pivotally mounted at its lower end on the locking bolt and having an inverted L-shaped slot extending transversely therethrough, a pin mounted on the locking bolt and extending through the slots in the pivotally-mounted tumbler-engaging element and in the short arm of the inverted L-shaped slot in the locking block to prevent relative movement between said locking bolt and said pivotally-mounted tumbler-engaging element, and a spring mounted on the locking bolt to move the tumbler-engaging portions into the tumbler recesses when said tumblers assume a release position, the movement of said tumbler-engaging portion freeing the pin from its position within the short arm of the L-shaped slot in the locking block and into a position within the long arm of the L-shaped slot in the locking block to permit the locking bolt to move into the recess in the driving wheel to release said locking bolt.
7. A combination lock mechanism comprising a driving wheel having a peripheral recess, a locking bolt adapted to enter into said recess in assuming a release position, tumblers each having a peripheral groove and each having a recess extending into said tumblers at the base of said groove, an element mounted on the locking bolt and having tumbler-engaging portions disposed in the grooves and adapted to enter the recesses in said tumblers when said tumblers assume a release position, and means to move the locking bolt into the recess in the driving wheel when said tumbler-engaging portions enter the recesses in said tumblers to release said locking bolt.
- 45 In testimony whereof, I sign this specification.

WILLIAM F. DOENGES.
